UNITED STATES PATENT OFFICE.

WILLIAM J. PUBLLOW, OF DETROIT, MICHIGAN, ASSIGNOR TO THE FARRAND COMPANY, OF DETROIT, MICHIGAN, A CORPORATION OF MICHIGAN.

SELF-PLAYING MUSICAL INSTRUMENT.

No. 897,656.

Specification of Letters Patent.

Patented Sept. 1, 1908.

Application filed June 3, 1908. Serial No. 436,383.

To all whom it may concern:

Be it known that I, WILLIAM J. PUBLLOW, a citizen of the United States of America, residing at Detroit, in the county of Wayne and State of Michigan, have invented certain new and useful Improvements in Self-Playing Musical Instruments, of which the following is a specification, reference being had therein to the accompanying drawings.

10 The invention relates to new and useful improvements in automatic musical instruments, and consists particularly in the construction of the striking pneumatic, and in detail in the construction of the connection 15 between the movable member of the striking pneumatic and the lifter bar whereby such a connection is simplified in construction and rendered noiseless in use, and whereby any adjustment desired may be obtained; also 20 means are provided for taking up any shrinkage between the clamp and the lifter rod block, all as more fully hereinafter described and particularly pointed out in the claims.

In the drawings—Figure 1 is a perspective view of a striking pneumatic as used in automatic musical instruments showing at the end thereof my improved connection; Fig. 2 is a side elevation thereof showing the clamp and striker rod block in vertical central section.

A represents the stationary board of a striking pneumatic, such as is ordinarily employed in automatic musical instruments, B the movable member or board thereof, and C the connecting fabric, the whole being a small bellows. It is well known in the art that when controlled by suitable valves this bellows is to be collapsible, such collapsing striking the blow which is to sound the desired note. It is customary to connect to the movable board of the striking pneumatic a lifter rod such as C'.

My manner of connecting the vertical rod to the movable board of the pneumatic comprises a clamp consisting preferably of sheet metal, and comprises a flat plate portion a which is secured to the movable board and the clamping portion b. The clamping portion is preferably a bifurcated or divided portion, leaving a space c between the two portions in the metal, and this is formed by bending the strips of the two furcations into circular form, as plainly shown in the drawings. Within this clamp or socket thus formed of the portions b I place a cross bar or

block D, preferably of leather or some other fibrous material, the portion b being clamped tightly down upon the same so as to hold it firmly in position. To the block or bar D I pass the end of the lifter rod C', this rod being 60 suitably screw-threaded, so that it may be adjusted to any desired length. At the upper end of the lifter rod C' I attach the usual head E. The furcations b, when they are bent around the block D, are bent so that the 65 ends thereof preferably are not in contact with the body portion a of the clamp, so that if the bar D should shrink, and thus loosen, the clamp may be tightened by further closing the clamp upon the bar. This can be done 70 by any ordinary tool which will squeeze the parts together. It is obvious from the drawings that the lifter rod C' passes through the bar D between the furcations b.

This construction is easily built, and is of 75 novel manufacture, and there is no danger of the parts becoming loosened. The striker rod block D forms a comparatively long bearing for the screw threads of the rod C' so as to hold both firmly in adjusted position, and so there is no danger of rattling or noise in the operation of the device.

What I claim as my invention is:

1. The combination of a fibrous block or bar, a lifter rod secured thereto, a clamp embracing the block or bar, and a movable member to which the clamp is secured.

2. The combination of a fibrous block or bar, a lifter rod secured thereto, a closable clamp embracing the block or bar, and a 90 movable member to which the clamp is secured.

3. The combination of a fibrous block or bar, a lifter rod adjustably connected thereto, a bifurcated clamp embracing the block or 95 bar on opposite sides of the lifter rod, and a movable member to which the clamp is secured.

4. The combination of a fibrous block, a lifter rod having a screw threaded engagement therewith near the middle, a bifurcated closable metal clamp bent around the bar on opposite sides of the rod, and a movable member to which the clamp is secured.

In testimony whereof I affix my signature 105 in presence of two witnesses.

WILLIAM J. PUBLLOW.
